CHECKERWORK AND BRICK THEREFOR

Truman H. Kennedy, McKeesport, Pa., assignor
to National Tube Company, a corporation of
New Jersey

Application August 10, 1945, Serial No. 610,023

10 Claims. (Cl. 263—51)

1

The present invention relates to improvements in heat exchanging checkerwork and more particularly to checkerwork and brick especially adapted for use in connection with hot blast stoves, such as are used for heating air for blast furnaces.

Formerly, the sizes and shapes of bricks and the method of laying the bricks in blast furnace stoves, had been reduced to a common practice, and this practice was accepted by builders and operators as very satisfactory, under the then existing conditions. The size of firebrick commonly used in such stoves was 10½" long x 6" wide x 2½" thick. The brickwork was laid in the pattern known as the basket weave, wherein the bricks came into close physical contact with each other, and the finished assembly became a closely bound and stable structure. The vertical flues formed by this geometric basket weave design were 4" square and the vertical walls forming this flue opening never exceeded the thickness of one brick or 2½". This flue area, of 16 square inches, was deemed necessary on account of the nature of the gas burned in the stove. At that time, the gas used for heating stoves was but partially cleaned and contained much dust. Moreover, the effective brick mass or ratio of effective brick mass to brick surface was relatively low and inefficient.

More recently, the practice of using raw dirty furnace gas to heat the stoves was discontinued. The gas is now thoroughly cleaned, to the extent that the gas used in a furnace stove is usually cleaner than outside atmospheric air. As a direct result of the elimination of dust from the gas, it is now the practice to construct the vertical flues in the checkerwork at a much reduced cross-sectional area. An opening of 2" x 2" cross section, or its equivalent in square inches is favorably considered by most builders and operators. It is naturally expected that a consequent reduction of the thickness of the brick to some dimension such as 1½" should follow the reduction of the flue area from 16 to 4 square inches. Assuming the brick has a thickness of 1½", the resultant length of this brick to form the favorite basket weave design would be 5½" long. A brick having a length of only 5½" would be entirely too short for practical use and does not find favor with builders and operators. As a result, designers and constructors have evolved a variety of brick designs and especially new patterns and constructions to obtain a maximum area of heating surface for the volume of checkers. Many of the new brick designs, while providing a high effec-

2

tive brick mass, are expensive to manufacture and are either fragile or unstable, or both.

It has also been proposed to use brick of substantially conventional width and breadth but increased depth or thickness with an elongated slot therein which will provide a central vertical flue when such bricks are superposed in cross-wise relation. This design permits laying the brick in basket weave with its attendant advantages and while the effective brick ratio is increased slightly over solid brick, the increase is so small that the increased efficiency is not enough to offset the increase in cost. Moreover, the flues in such structure are of unequal size and do not provide an even flow of air therethrough and, since the flues are not of equal size, the ratio of flue surface to brick mass area is not constant and consequently undesirable.

Accordingly, it is an object of the present invention to provide a basket weave checkerwork having maximum heating surface per unit of mass.

It is another object of the present invention to provide a multi-flued basket weave checkerwork that may be either columnar or cross-bonded.

It is a further object to provide a multi-flued checkerbrick that may be laid in basket weave in either columnar or cross-bonded design.

It is a still further object to provide multi-flued checkerbrick that may be laid in basket weave with substantially equal size flues.

The foregoing and further objects will be apparent from the specification and drawings, wherein:

Figure 1 is a plan view of a preferred form of the checkerbrick of my invention;

Figure 2 is an elevation thereof;

Figure 3 is an isometric view of checkerwork laid in cross-bonded relation;

Figure 4 is a section on line IV—IV of Figure 3;

Figure 5 is a plan of a modified form of checkerbrick; and

Figure 6 is a similar view of a further modification.

Referring more particularly to the drawings, the numeral 2 designates a refractory brick in the form of a rectangular parallelepiped through which there is a central vertically extending opening or flue 4. The flue 4 is perpendicular to the planes or faces 8 of repose of the brick as laid to form checkerwork. At opposite ends of the brick 2 are open-ended flues 6 which are parallel to the flue 4. An open-sided flue 10, normal to the flue 4, is provided in one of the faces 8 and

extends thereacross intersecting the central flue 4.

The brick 2 is of substantial thickness to give individual brick stability and convenience of handling. The width 12 of the brick is sufficient to insure proper thickness of wall and is therefore dependent on the number of flues across the width of the brick. The length 14 of the brick 2 is directly dependent upon the dimension 16 of the central flue 4. The length 14 exceeds or is equal to the brick width 12 plus twice the dimension 16 across the internal flue, which is generally substantially square but may be circular or otherwise as desired. Thus, it follows that the open-ended flues 6 have substantially the same area as the central flue 4 and may be of generally similar geometrical form. However, in the case of square openings, it is desirable that the end flues be heavily filleted in the form of a radius 18 to strengthen the cantilevered fins 20 against breakage in handling and to provide strength for supporting superposed brick to form checkerwork.

From the foregoing, it appears that by properly proportioning the wall thickness of the brick so that it is all usable as a heat exchange medium, the brick mass is effectively used and due to the provision of effective flue surface or area that a high ratio of 95% or greater of ratio of brick mass to heating surface is obtained.

By reference to Figures 3 and 4 of the drawings, wherein fragmentary views of checkerwork composed of brick 2 are shown, it is seen that the bricks are laid in courses of a continuous longitudinal-lateral abutment pattern forming the so-called basket weave. By reason of such courses the open-ended flues 6 are closed by being abutted against a vertical side of the adjacent brick. Since the end flues 6 are closed by the abutted sides of the adjacent brick, relative shifting thereof will not vary the flue area. In addition, due to the aforementioned length 14 of the brick exceeding the width 12 by twice the flue dimension 16, there is formed centrally within each four bricks 2, in laid-up position, an additional "free" flue 22 having substantially the same area as the flues 4 and 6.

The superposed courses of brick as shown in Figures 3 and 4 may be laid in cross-bonded relation so that the superposed individual bricks are at right angles to each other with the central flues or openings 4 in alignment. By reason of such arrangement, it is noted that each central flue 4 is connected to the end flues 6 of the abutting brick on either side. This provides alternating cross-draft to increase the heating surface and to serve as by-passes when either flues 4 or 6 become completely or partially plugged.

Such cross-bonded relation in checkerwork is particularly desirable in the lower portion of a hot blast stove since it provides the greatest possible rigidity and strength. The ends of the brick being abutted against the sides of the adjacent brick provide stability and resistance to turning caused by the alternate heating and cooling of the checkerwork. If desired in the upper portion of the stove, the bricks may be laid in columnar form, that is, with the superposed bricks in vertical alignment, without affecting the flue areas. This may be desirable since such courses are easier to lay and permit maximum free vertical expansion in the hottest region of the stove.

In Figures 5 and 6, I have shown modified forms

of checkerbrick which achieve the foregoing results and can be laid in basket weave in either cross-bonded or columnar form. It is seen that the number of central flues 4' in these modifications is equal to the square of the number of end flues 6' at either end of the brick. Moreover, it is noted that the central flues are arranged in rows so that each row has the same number of flues as the number of end flues. Due to this spacing and arrangement, if a brick is superposed at right angles on a brick, the flues can be aligned in the same manner as the single-flued brick. In this case, also a high ratio of heating surface per unit of brick mass is obtained, making such brick efficient to use. Also they have the same inherent stability of basket weave as is obtained by the single-flued brick.

While I have shown and described several specific embodiments of my invention, it will be understood that these embodiments are merely for the purpose of illustration and description and that various other forms may be devised within the scope of my invention, as defined in the appended claims.

I claim:

1. A checkerbrick comprising a refractory rectangular parallelepiped having at least one central vertical opening therethrough and an open-ended flue on each end thereof in substantial alignment with said central opening, said open-ended flue having substantially the same area as said central opening, the length of said checkerbrick being approximately equal to the width plus twice the diameter of said central opening.

2. A checkerbrick comprising a refractory rectangular parallelepiped having at least one central vertical opening therethrough and at least one open-ended flue on each end thereof, each of said open-ended flues having substantially the same diameter as said central opening, the number of said central flues being the square of the number of open-ended flues on either end of said brick, said central flues being so disposed that the flues in a superposed brick disposed at right angles will be in alignment therewith.

3. Checkerwork comprising a plurality of courses of rectangular brick, each brick having a central vertical flue and open-ended vertical flues at each end thereof, the alternate brick in a course being disposed at right angles to the intermediate brick to close said open-ended flues.

4. Checkerwork comprising a plurality of courses of rectangular brick, each brick having a central vertical flue and open-ended vertical flues at each end thereof, the alternate brick in a course being disposed at right angles to each other to close said open-ended flues and form closed vertical flues having substantially the same area as said central flue.

5. Checkerwork comprising a plurality of courses of rectangular brick, each brick having a central vertical flue and open-ended vertical flues at each end thereof, the alternate brick in a course being disposed at right angles to each other to close said open-ended flues by perpendicularly abutting the ends of said brick against the mid-portion of the adjacent side of the adjacent brick to form closed vertical flues and to form vertical flues between the brick, said closed vertical flues and the flues formed between said brick having substantially the same area as said central flue.

6. Checkerwork comprising a plurality of courses of rectangular brick, each brick having a central vertical flue, an open-ended vertical

flue at each end thereof and a horizontal open-sided flue extending across said vertical flue, the alternate brick in a course being disposed at right angles to each other to close said open-ended flues by perpendicularly abutting the ends of said brick against the mid-portion of the adjacent side of the adjacent brick and superposed courses being placed with the vertically adjacent brick at right angles to each other to connect said central flue with the open-ended flue of the adjacent brick on either side thereof by said horizontal flue.

7. Checkerwork comprising a plurality of courses of rectangular brick, each brick having a central vertical flue, an open-ended vertical flue at each end thereof and a horizontal open-sided flue extending across said brick to intersect said central flue, the alternate brick being disposed at right angles to each other to close said open-ended flues by perpendicularly abutting the ends of said brick against the mid-portion of the adjacent side of the adjacent brick and form vertical flues having substantially the same area as said central flue and superposed courses being placed with vertically adjacent brick at right angles to each other with the central flue aligned to connect said central flue with the open-ended flue of the adjacent brick on either side thereof by said horizontal flue.

8. Checkerwork comprising a plurality of courses of rectangular brick, each brick having at least one vertical flue therethrough and at least one open-ended vertical flue at each end thereof, the alternate brick in a course being disposed at right angles to each other to close said open-ended flues by abutting the ends of each brick against the mid-portion of the adjacent side of the adjacent brick.

9. A checkerbrick comprising a refractory rectangular parallelepiped having at least one vertical flue therethrough and having at least one open-ended flue on each end thereof, the num-

ber of said central flues being the square of the number of open-ended flues on either end thereof, said central flues being so disposed that the flues in superposed right angularly disposed bricks will be in alignment, the side walls of said brick being substantially flat whereby the open-ended flues of a right angularly disposed brick in contact therewith will be closed by said flat side walls and form flues having substantially the same area as said central flues.

10. A checkerbrick comprising a refractory rectangular parallelepiped having at least one vertical flue therethrough and having at least one open-ended flue on each end thereof, the number of said central flues being the square of the number of open-ended flues on either end thereof, said central flues being so disposed that the flues in superposed right angularly disposed bricks will be in alignment, the side walls of said brick being substantially flat throughout their length whereby the open-ended flues of a right angularly disposed brick in contact therewith will be closed by said flat side walls.
